DUSTING MACHINE

Walter C. Perren, Hastings, Minn., assignor to
H. D. Hudson Manufacturing Company, Chi-
cago, Ill., a corporation of Minnesota

Application December 21, 1936, Serial No. 116,894

13 Claims. (Cl. 43—148)

This invention relates to improvements in devices for disseminating dust by blowing, and has among its objects to generally improve the device and to provide specific instructions whereby the operation is improved and the center of gravity of the device is arranged closer to the body of the user. Features include all details of construction shown along with the broader ideas of means inherent in the disclosure.

10 A feature of the invention is also to provide a device in which the center of gravity of the blower and supply hopper, and particularly of the hopper, is as near to the body of the user as is possible and at the same time to obtain the maximum blower and supply capacities, such optimum conditions being possible as a result of the closer spacing of the parts in a forward-rearwardly direction relatively to the thrust plate, and by having the upper part of the hopper overhang the fan casing, and with the rear of the hopper adapted to lie near to or engage the chest of the user.

20 Another feature is the arrangement of the crank shaft close to the body and near the thrust plate, and with the crank handle so placed as to operate in a plane which lies laterally of and close to the body of the user, in a position which allows a more natural and easier manipulation, thus making it easier to prevent lateral swinging of the device when in use, which swinging occurs readily when the crank shaft is more forwardly placed.

25 Another feature of the invention relates to the provision of a handle brace by which the device is steadied, and the use of straps attached to the brace (and therefore at a forward part of the structure) to pass over the shoulders to be finally connected with the ends of the thrust plate in a manner to resist lateral movement of the plate and steady the structure relatively to the body of the user.

30 Another object of the invention relates to the utilization of the suction and gear casings as means for rigidly securing the fan casing and hopper together. Another feature relates to the horizontal feed laterally into a short suction conduit and laterally from the suction conduit to the middle of the fan, and a peripheral discharge by the fan assisted by gravity, and delivered into a forwardly leading horizontal spout, the bottom wall of which is tangential to the bottom of the fan casing, whereby delivery efficiency is much enhanced, and compactness is achieved, and the center of gravity of the struc-

ture is kept as near to the body of the user as possible.

35 Objects, features and advantages of the invention will appear in the description of the drawings forming a part of this disclosure, and in said drawings:

Figure 1 is a view showing a device as in use;

Figure 2 is a sectional elevation taken through the suction conduit, on line 2—2 of Figure 5;

Figure 3 is a plan section taken through the 10 hopper on line 3—3 of Figure 4;

Figure 4 is a vertical longitudinal section taken approximately on line 4—4 of Figure 5; and

Figure 5 is a horizontal section taken on line 5—5 of Figure 4.

40 In the drawings the numeral 1 indicates a curved supporting and thrust plate having at its end slots 2 for the reception of straps later to be described. This plate is adapted to engage the front of the body of the user approximately at the waist line, and the plate supports a structure which lies forwardly of it. This structure includes a forwardmost fan casing 3 having a forwardly leading discharge spout 4 the bottom wall of which is substantially tangential with the bottom wall of the casing. In this casing is a fan 5 mounted on suitable cross shaft 6 which lies horizontally when the device is in use. One wall of the fan casing has suction openings 7 which may be said to circumscribe this shaft, 50 for the purpose of directing the material to the middle of the fan, to be thereafter discharged peripherally. Placed immediately rearwardly of the fan casing 3 is an upstanding supply hopper generally indicated at 16. The hopper has a 55 relatively small semi-cylindrical bottom, the axis of which is parallel with and lies in the same horizontal plane as the fan shaft. The bottom merges into a larger upper part, a portion of which overhangs the fan casing. The hopper thus has a relatively large capacity and its rear is adapted to be near to or engage against the chest of the user. The hopper is however of such a height that the user can easily see over it and thus the forward view is not obstructed.

55 The hopper thus has a lower portion which is constricted in horizontal area as compared with the upper portion, with said lower or delivering portion being disposed immediately adjacent the rear curved periphery of the fan casing. The upper portion of the hopper overhangs the fan whereby large hopper capacity is obtained, and whereby minimum length of travel of the material in the conduit 40 is obtained and whereby front and rear compactness is obtained with

large hopper capacity and the location of the center of gravity immediately adjacent the body of the user.

The bottom portion 11 of the hopper has there-
5 in a cross-shaft 12, which when the device is
in use is substantially in the same horizontal
plane as the cross-shaft 6 of the fan. This semi-
cylindrical bottom merges into vertical walls,
10 these merge into flaring walls 15 which in turn
merge into an upper cylindrical wall portion 16',
the axis of which is vertical. A suitable cover
15 17 is provided which has a handle 18. The cover
has means generally indicated at 19, by which
it can be detachably secured to the hopper as
a result of rotation. The hopper is connected
20 to the thrust plate 1 by a U-shaped structure
welded to the side of the bottom portion of the
hopper and having extensions 20 which engage
against the inner side of horizontal flanges 21
25 of the thrust plate. Any suitable means may be
used for making this connection. It is noted
that the rear of the hopper is almost in the ver-
tical plane of the forwardmost part of the curved
thrust plate.

25 By the arrangement shown a very compact
structure is provided in which the center of grav-
ity is at a minimum distance from the user, and
in which a relatively large fan capacity as well
as a relatively large hopper capacity is obtained.
30 Another feature of the invention is the use of
a steady handle which also functions as a
bracing means. This handle 25 is connected to
and rises from the top of the fan casing 3, and
has a substantially horizontal upper portion 26
35 which is secured or connected to the vertical
cylindrical wall 16' of the hopper as shown. To
this horizontal portion is connected a ring 27
and to this ring is connected a strap or strap
sections 28 which pass slantingly and divergently
40 upwardly and over the top of the hopper (and
clear of the hopper) and over the shoulders of
the user, thence downwardly to cross one another
and then pass between the arms and be connected
in the slots 2 of the thrust plate 1. These straps
45 when connected tend to hold the plate against
the body and to prevent lateral movement of the
device during operation.

Another feature of the invention relates to the
scheme of lateral feed from the hopper into a
50 laterally disposed short horizontal suction con-
duit 40 which leads horizontally forwardly and
delivers horizontally at the middle of the fan
through the openings 1 or their equivalent, to be
peripherally discharged at a point below its entry
55 point, whereby gravity assists delivery into spout
4. To this end the shaft 12 is provided with
axially spaced spiral means generally indicated
at 30, 31, see Figures 4 and 5, which rotate with
the shaft and feed the dust outwardly through
60 radially arranged slots 35, arranged forwardly
of the shaft 12 and with which corresponding
slots 36 of a valve plate 37 are registerable to
control outflow, see Figure 5. The plate is rotatable
on bearing 39 of the shaft 12, which bearing
65 projects into the suction conduit.

The horizontal suction conduit 40 establishes
communication between the openings 36 and the
openings 1 or between the hopper and the fan.
Into this conduit the feeding means delivers ma-
70 terial from the hopper and from it the material
is delivered to the middle of the fan. The con-
duit also acts (and this is a feature) to secure
the fan casing 3 and hopper rigidly together.

75 Referring to Figures 2 and 5 another feature
is the arrangement of a valve plate 37 and the

handle 45 controlling it. It will be noted that
the control handle is arranged forwardly of the
thrust plate 1, and rearwardly of the hopper.
It is further noted that the conduit is open as at
46 to admit air at a point rearwardly of the entry
5 point of the material from the hopper.

Referring to Figure 2 and reverting to the
advantages of the arrangement of the conduit,
it will be seen that the dust is delivered into a
short conduit at a point forwardly of the shaft 10
12 and at a point quite near to the opening 1.
In other words, it has only a short distance to
travel. This is partly due to the narrowing of
the lower part of the hopper. Moreover, the
dust is delivered at the middle of the fan and is 15
assisted by gravity to the delivery point or spout,
the bottom of which is below the axis of rotation
of the fan.

Another feature of the invention is the ar-
rangement of a crank 50 connecting with the 20
shaft 12, which shaft is at the lower part of the
system and as near to the body as possible. The
crank handle 51 is disposed to operate substan-
tially in a plane which lies laterally of the body
of the user, the crank 50 being slanted, as shown 25
in Figure 5, for this purpose.

At that side of the device opposite the suction
conduit is arranged another casing indicated at
53 and in which is disposed gearing or equivalent
drive means generally indicated at 54, by which 30
operation of the shaft 12 rotates the fan shaft.
The gearing is of such nature that high speed of
the fan can be obtained by relatively lower speed
rotation of the crank 50. The gear train in-
cludes a gear 55 on shaft 12 and a gear 56 on 35
the fan shaft 6. The casing is made in sections
secured as at 57.

Another feature is the construction of the fan
which comprises two plates 60, one at each side
of the shaft 6, attached to the shaft by any suit-
able means indicated at 61. This is a cheap and
efficient structure.

Other features of the invention relate to the
lateral feeding means; to the means for stirring
the material in the hopper; and to the operation 45
of this stirring means from the same shaft which
controls the lateral feeding means.

The lateral feeding means have previously
been referred to by the numerals 30 and 31, see
Figure 5. Each comprises spirally arranged and 50
spirally acting members which are suitably at-
tached to the shaft and rotated thereby to push
the material toward and through the openings.
This occurs when the shaft is rotated in counter-
clockwise direction as viewed in Figure 4. 55

Referring now to Figure 3, there is arranged in
the upper part of the hopper a rocking stirrer
device formed from wire and including ends 70
journaled as shown in the hopper and provided
with horizontal loop portions 71, 72 lying at op-
posite sides of a line passing through the center
of the hopper and extending in opposite direc-
tions from the axis of rotation. The loops are
connected by a short portion 73 which is ec-
centric to the rocking axes 70. With this por-
tion 73 is connected a pitman 75 which at its
lower end is connected with a ring indicated at
76 which ring is in part held in a position ec-
centric to shaft 12 by and on two cross pins 78
in turn bridging and carried by a pair of plates
79 which are secured in axially spaced relation on
the shaft, as best shown in Figure 5. The shaft
12 or sleeve thereon forms with the pins 78
means for holding the ring in eccentric relation.
It is clear that when the shaft 12 is rotated the 75

eccentric, acting through the pitman 75, upon the eccentrically disposed portion 73, rocks the stirrer loops 71, 72 to agitate the material.

The element 30 is arranged near the openings 35 and has inclined faces so disposed as to wipe or feed the material toward and through the openings, somewhat in the manner of a spatula, breaking up the material at point of entry through the openings and assuring fine division 10 before delivery into the suction conduit. This is a feature.

I claim as my invention:

1. A dust disseminating device including a forwardmost blower fan casing having a delivery 15 spout leading tangentially from its bottom, a hopper close to and behind the casing having means for feeding material laterally therefrom and from the bottom, and a short horizontal conduit establishing communication between the 20 hopper and the fan casing and delivering centrally of the fan, whereby the material is assisted by gravity to be discharged from the lower part of the fan casing through said spout.

2. A dust disseminating device including a forwardmost blower fan casing and fan therein having a horizontally arranged cross-shaft, a delivery spout leading forwardly from and tangentially related to the bottom of the casing, an 25 upstanding supply hopper arranged rearwardly of and immediately adjacent the fan casing and having in its bottom a cross-shaft and means on the shaft for feeding material laterally from the hopper, said cross-shafts being substantially 30 in the same horizontal plane when the device is in use, means for driving the shafts, and a short horizontal suction conduit establishing communication between the hopper and the fan, and into which the feeding means delivers material from the hopper, and by which the material is delivered to the middle of the fan, thence to the 35 bottom of the fan casing and to said spout, said conduit being open at a point rearwardly of the point of entry of material from the hopper.

3. A dust disseminating device having, a supporting and thrust plate adapted to engage the front of the body of the user approximately at the waist line, a structure supported by and arranged horizontally and extending forwardly from the plate including a forwardmost blowing fan casing and fan therein, a delivery spout, an upstanding supply hopper arranged rearwardly of and immediately adjacent the fan casing and rising thereabove and adapted to be near or against the chest of the user, and a steady 50 ing handle brace disposed forwardly of the hopper and attached to and arising from the fan casing and connected by its upper portion to the hopper, and serving as means by which the thrust plate is pressed firmly against the body of the user.

4. A dust disseminating device including, a supporting and thrust plate adapted to engage the body of the user, a structure supported by and extending forwardly from the plate including, a forwardmost blower fan casing and fan 55 therein having a horizontally arranged shaft, a forwardly leading delivery spout for the casing, an upstanding supply hopper arranged rearwardly of and immediately adjacent the fan casing and rising thereabove and having at its bottom a shaft and means on the shaft for feeding material laterally from the hopper, said shafts lying in a horizontal plane which cuts the thrust plate, means by which material from the hopper is delivered to the fan, and means for operating 60 said last mentioned means and said fan includ-

ing a crank as an extension of said hopper shaft and having a handle so disposed as to operate substantially in a plane which lies laterally of the body of the user.

5. A dust disseminating device including, a forwardmost blower fan casing, and fan therein having a cross shaft, a delivery spout leading forwardly from the casing, an upstanding supply hopper arranged rearwardly of and immediately adjacent the fan casing and rising thereabove and having at its bottom a cross-shaft and means on the shaft for feeding the material laterally from the hopper, and a pair of casings one arranged laterally at each opposite side of the fan casing and hopper and serving to rigidly connect the same, one of the casings forming a conduit by which dust is led from the hopper to the fan casing and the other having therein means by which one of the shafts drives the other. 20

6. A dust disseminating device having, a supporting and thrust plate adapted to engage the front of the body of the user and a structure supported by and extending forwardly from the plate including, a forwardmost blowing fan casing and fan therein, a delivery spout leading tangentially forwardly from the bottom of the fan casing, an upstanding supply hopper arranged rearwardly of the fan casing and rising thereabove, a steady handle and brace connected to and rising from the fan casing and secured to the hopper forwardly thereof, a laterally disposed suction conduit which communicates with the fan casing and hopper and secures them together, a casing at the opposite side of and securing the fan casing and hopper together, and means in part within said casing for controlling hopper feed into the conduit, and operating the fan. 30

7. A dust disseminating device having, a supporting and thrust plate adapted to engage the front of the body of the user and a structure supported by and extending forwardly from the plate, including a forwardmost blowing fan casing and fan therein, a delivery spout leading forwardly from the fan casing, an upstanding supply hopper arranged rearwardly of the fan casing and rising thereabove, said hopper having lateral openings therein, a horizontal cross-shaft in the hopper, means on the shaft for delivering dust through the lateral openings of the hopper, said fan casing having receiving openings in its lateral wall surrounding the fan shaft, a delivery and suction conduit connecting said lateral and receiving openings, and which conduit has a rear open end through which air can be sucked, said end being spaced forwardly of the thrust plate, and valve means controlling entry of dust from the hopper opening into the conduit, and having a control handle accessible at a point forwardly of the thrust plate and rearwardly of the hopper. 40

8. A dust disseminating device having a supporting and thrust plate adapted to engage the front of the body of the user approximately at the waist line, a structure supported by and extending forwardly from the plate including a forwardmost blowing fan casing and fan therein, a delivery spout leading forwardly from the casing, an upstanding supply hopper arranged rearwardly of and immediately adjacent the fan casing and rising thereabove and adapted to be near or against the chest of the user, when the thrust plate engages the user, means in the hopper for feeding dust laterally therefrom, a suction conduit leading from the hopper to the fan casing 70

and fan and disposed laterally of the casing and hopper and serving to secure them together, a gear casing at the opposite side of the fan casing and hopper serving to secure them together, 5 gearing in said gear casing for operating the fan and feeding means, a crank for operating the gearing which is journaled in the bottom of the hopper and which has a handle so disposed as to operate substantially in a plane which lies laterally of the body of the user.

10. A dust disseminating device in which the center of gravity is at a minimum distance forwardly of the user, comprising a supporting and thrust plate adapted to engage the front of the body of the user approximately at the waist line, a structure supported by and extending forwardly from the plate including, a forwardmost blowing fan casing and a fan therein, a delivery spout leading tangentially forwardly from the bottom 15 of the casing, an upstanding supply hopper arranged rearwardly of and immediately adjacent the fan casing and rising thereabove and adapted to be near or to engage against the chest of the user when the thrust plate engages the user, a 20 steady handle-brace spaced forwardly from the hopper and attached to and arising from the fan casing and connected at its top to the forward side of the hopper, a pair of straps having their forward ends 25 attached to the upper part of the handle and adapted to pass slantingly and divergently upwardly and over the top of the hopper and clear of the hopper and over the shoulders of the user, and thence downwardly to cross one another and 30 then pass between the arms and the body and be connected with the ends of the thrust plate to support and to prevent undue lateral motion of the plate, a dust-forwarding conduit leading from the hopper to the fan casing and disposed at one 35 side of each, and means for operating the fan and stirring the contents of the hopper, including a crank journaled in the bottom of the hopper and having a handle so disposed as to operate substantially in a plane which lies laterally of 40 the body of the user.

45. A dust disseminating device having a supporting and thrust plate adapted to engage the front of the body of the user approximately at

the waist line, a structure supported by and arranged horizontally and extending forwardly from the plate including a forwardmost blowing fan casing and fan therein, a delivery spout, an upstanding supply hopper arranged rearwardly of and immediately adjacent the fan casing and rising thereabove and adapted to be near or against the chest of the user, a steady handle-brace spaced forwardly from the hopper and attached to and arising from the fan casing and 10 connected at its top to the forward side of the hopper, means for feeding material to the fan and means for operating the fan and feeding means including a crank journaled in the bottom of the hopper and having a handle so disposed as to operate substantially in a plane which 15 lies laterally of the body of the user.

15. A dust disseminating device having a hopper having openings in its lateral wall through which material is delivered, a shaft and a plurality of plates thereon having spiral blades acting when the shaft is rotated to move the material laterally and through said openings, one of said 20 blades being disposed to wipe and press the material against said lateral wall and through said 25 openings.

20. A dust disseminating device having a hopper having openings in its lateral wall through which material is delivered, a shaft, and a plate thereon having spiral blades acting when the shaft is rotated to move the material laterally 30 and through said openings, said blades being disposed to wipe and to press the material against said lateral wall and through said openings.

25. A dust disseminating device having a hopper having openings in its lateral wall through which material is delivered, a shaft, and means thereon acting when the shaft is rotated to move the material laterally and through said openings, a stirrer arranged in the hopper to rock on a 35 horizontal axis, and having a portion eccentric to its rocking axis, eccentrically acting means on said shaft within the hopper, and means connecting said eccentrically acting means with said eccentric portion of said rocking axis for rocking the stirrer when the feed shaft is rotated to feed 40 the material laterally.

45. WALTER C. PERRON.
